UNITED STATES PATENT OFFICE.

ALBERT M. KING, OF CASPER, WYOMING.

BOMB.

Application filed September 19, 1925. Serial No. 57,451.

To all whom it may concern:

Be it known that I, ALBERT M. KING, a citizen of the United States, and resident of Casper, in the county of Natrona and State of Wyoming, have invented certain new and useful Improvements in Bombs; and I do hereby declare the following to be a full, clear, and exact description of the invention, such as will enable others skilled in the art to which it appertains to make and use the same.

This invention relates to bombs for use in shooting oil wells, and more specifically to a bomb provided with timed mechanism controlling the explosion of the charge.

It is broadly old in the art to provide time controlled mechanisms to electrically ignite the charge carried by a bomb, but there is grave danger in the employment of such a device, due to the fact that, when such mechanism is actuated, the explosion is practically instantaneous. In the oil fields many fatalities have occurred because of careless manipulation of such bombs, while setting the timing mechanism, or in accidentally dropping the bomb while such mechanism is set in safety position.

The primary object of the present invention therefore is the provision of a bomb such as described, equipped with timing mechanism adapted to initiate the operation of certain instrumentalities which finally lead to the explosion of the bomb, but which operate to delay such explosion for a predetermined period, even after the timing mechanism has been released or sprung. It follows therefore that, in the use of the device embodied in the application, if the timing mechanism is accidentally released, ample time is provided for the operator to disrupt one of the instrumentalities which is necessary to the explosion.

Another object of the invention is the provision of means for giving audible indication of the fact that the timing mechanism has been released.

Other objects of the invention will be made apparent in the accompanying specifications, when read in connection with the drawings forming a part thereof.

This application discloses certain subject matter in common with matter disclosed in my co-pending applications Ser. Nos. 6,109, filed Jan. 31, 1925, allowed April 13, 1925, and Ser. No. 10,098, filed Feb. 18, 1925, allowed April 20, 1925.

In the drawings:

Fig. 1 is a vertical section taken through a bomb casing equipped with my invention, the timing mechanism being shown in full lines. 60

Fig. 2 is a top elevation of the timing mechanism in "set" position.

Fig. 3 is a top elevation of the timing mechanism in its released or firing position.

Fig. 4 is a detailed perspective view of 65 the firing hammer associated with the timer mechanism.

Fig. 5 is a detailed perspective view of the clamps for holding the fuse end in position for contact by the hammer. 70

Fig. 6 is a view similar to Fig. 1, showing a modified fuse lighting mechanism.

Fig. 7 is a top plan view of the fuse-lighting mechanism shown in Fig. 6.

Fig. 8 is a view showing a modified form 75 of fuse igniter, substituting an abrasive for a hammer, and,

Fig. 9 is a perspective view showing means for holding the fuse in proper position.

Now referring specifically to the drawings, 80 in which similar reference numerals indicate like parts throughout the several views, 1 is a metallic casing which may be of suitable material, and of any desired dimensions, provided with a screw-cap 2. The 85 casing 1 is divided by a transverse partition 3, the upper portion of the casing being adapted to receive the timing mechanism, and the lower portion being filled with the explosive charge 4. 90

The timing mechanism is here shown as consisting of a small alarm clock 5, of the well known type, and the controls of the timing mechanism extend through the back of the clock, here shown at the top. Such 95 controls are the time-wind 6, the hand-set 7, the alarm wind shaft 8, the alarm set 9, and the lever 10 which renders the alarm operative or inoperative. To the rear outer surface of the clock casing, as here shown, 100 is bolted a semi-tubular metallic shell 11 which carries the mechanism which cooperates with the clock in initiating the train of instrumentalities leading to the explosion of the charge 4. A shelf 12 extends across the shell 11, just above the controls, and is bolted at each end to a side of the shell, one end of the shell being turned backwardly from the shell and extended over itself to form a support 13, which extends inwardly 105 of the shell to a point beyond the center thereof, as clearly shown in Fig. 1.

A slow-fuse 14 extends from above the the hammer head 30 moves in anti-clock-
clock 5, along the outside thereof and is wise direction around the pin 27 and comes
operatively connected at its lower end to a to rest with its front face against the rear
percussion cap 15 seated in a port provided face of the clamping members 16, the fir-
centrally in the partition 3, the cap contact- 70
ing or being closely adjacent the explosive ing pin 31 is at rest in the aperture 22,
charge in the lower portion of the casing 1. having contacted and exploded the fulmi-
In order to properly position the upper end nate 26, thus lighting the fuse 14. The
of the fuse for lighting by the timing mech- spring 32 always exerts its influence to
anism, I provide two co-operating clamp- swing the hammer in an anti-clockwise
ing members 16 and 17, as clearly illustrated 75
in Figs. 1 and 5. The member 16 is trans-
versely slotted at 18, to permit entry of
the front edge of the shelf 12, and an up-
standing shoulder 19 is formed upon the top
thereof, against which the edge of the sup-
port 13 abuts when the member is secured
in operative position by means of a screw
20, which extends through the support 13
25 and into the top of the member 16. The
front face of the member 16 carries a round-
ed groove or trough 21, extending from the
bottom to a point considerably above the cen-
tral line of the member, and, at the top of
25 the groove 21, is formed a perforation 22
extending transversely through the member
and opening through the rear wall thereof
as shown in Fig. 3.

The member 17 is formed to complement
30 the member 16 in clamping the fuse, and,
to that end is provided with a groove 23,
preferably carrying the upset spurs adapted
to enter the outer covering of the fuse and
prevent withdrawal thereof. The upper
35 portions of each of the members 16 and 17
are provided with screw-threaded apertures
for the reception of a screw 24, which draws
the members together and rigidly clamps the
fuse therebetween. To impart added rigidity
40 to the structure, a screw 25 may extend
through the shell 11, through the support
13, and into the side wall of the member
16, as shown in dotted lines in Fig. 1.

In actual practice the top portion of the
45 fuse is provided with a fulminate 26, such
as a match head, which is to be positioned
in the aperture 22 for contact by the firing
pin of the hammer to be hereinafter de-
scribed, the outer clamping member 17 be-
50 ing then secured in position.

As before stated the support 13 extends
above the shelf 12, and a pin 27 is extended
55 through aligned apertures in said shelf and
support, and firmly secured in position, said
pin also extending through ears 28, 28, of
a hammer arm 29, carrying a hammer head
30, provided with a firing pin 31, at its end,
as clearly shown in Fig. 4. A strong coiled-
spring 32 surrounds the pin 27, the lower
60 end 33 of said spring being hooked over
the edge of the shelf 12, and the upper
end 34 being hooked through an aperture
in the upper portion of the arm 29. The in-
strumentalities described are of such pro-
65 portions, and are so assembled, that, when

the hammer head 30 moves in anti-clock-
wise direction around the pin 27 and comes
to rest with its front face against the rear
face of the clamping members 16, the fir-
ing pin 31 is at rest in the aperture 22,
70 having contacted and exploded the fulmi-
nate 26, thus lighting the fuse 14. The
spring 32 always exerts its influence to
swing the hammer in an anti-clockwise di-
rection. 75

In order to "set" the hammer 30 and
retain it in armed position, I provide a de-
tent 35, which is secured at one end by
a screw 36, extending through the shell 11,
as clearly shown in Figs. 2 and 3. The
detent 35 is of resilient metal, and normally
extends into the shell 11 above the plane
of the clock 5. Extending below the ham-
mer head 30, is a lug 37, and, during move-
80 ment of the head 30, in clock-wise direc-
tion, the lug 37 bears against the inner face
of the detent 35 and presses it backwardly
towards the shell 11. Near the free end
of the detent 35 however is provided an
85 integrally-formed projection 38 and, as the
lug 37 passes the end of the projection 38,
the detent snaps forwardly towards the lug
and the latter thereafter cannot pass the
projection 38 in anti-clockwise movement.
90 This construction provides means for set-
ting the timing mechanism. 95

In order to release the mechanism just
described, whereby to permit the firing pin
31 to explode the fulminate carried by the
fuse, I provide the instrumentalities now
100 to be described.

The extreme end of the detent 35 is bi-
furcated to form two arms 39 and 40, ter-
minating adjacent the path of the shaft
8 of the alarm wind of the clock 5. As
105 is well known, the alarm wind shafts of
alarm clocks rotate in a clockwise direction
during the sounding of the alarm. I have
changed the finger grip with which such
shafts are usually equipped, and have se-
cured thereto a blade 41 mounted rigidly
upon the top of the shaft 8, and extend-
ing laterally thereof at one side only, as
best shown in Fig. 1. The blade 41 is pro-
110 vided with a vertically extending slot 42,
adapted to receive the arm 39, and the lower
portion of the blade 41 carries a cammed
portion 43, best seen in Figs. 2 and 3, adapt-
ed, during the rotation of the shaft 8 under
the alarm mechanism, to contact the rounded
115 inner face of the arm 40, and to push the
said arm, and therefore the detent 35, to-
wards the shell 11.

In actual practice the clock controls are
all accessible to the fingers of the operator,
except the time wind for the clock, and it
will be noted that the shaft 6 thereof is
shown slotted for a suitable tool for wind-
ing. The shaft 8 for the alarm wind may
120 be turned by the blade 41, while the detent
125

35 is pushed back against the wall of the shell 11. When the shaft 8 is almost fully wound, the outer end of the detent is released, whereupon the arm 39 thereof swings 5 into the plane of rotation of the blade 41. The arm 29 is then rotated clock-wise until the lug 37 engages behind the projection 38, at which time the blade 41 is turned slightly in anti-clockwise direction so as to 10 cause the arm 39 to enter the slot 42 in the blade, see Figs. 1 and 2, the parts being so proportioned as to readily adapt themselves to this position. It will be noted that, with the arm 39 in the slot in the 15 blade 41, the device is in safety position, since the lug 37 cannot be released from behind the projection 38 except by movement of the detent 35 towards the shell 11, and that such movement is prevented by 20 the wall defining the slot 42 in the blade 41. The device is now in "set" and also in "safety" position, and ready for insertion into the well to be shot.

At the proper time, dependent upon the 25 alarm setting, the alarm mechanism is set off and the shaft 8 immediately initiates clock-wise rotation. The first movement turns the blade 41 so that the slot no longer surrounds the arm 39, and continued rotation of the shaft causes the cammed portion 43 to brush against the curved face of the arm 40, and thereby move the very resilient detent 35 towards the shell 11. Such movement carries the projection 38 30 away from in front of the lug 37, releasing the arm 29, and the hammer 30 snaps the firing pin 31 into the aperture 22 and ignites the fulminate 26 and the fuse 14. The fuse burns to the cap 15 which 35 explodes and detonates the charge 4.

Obviously the delicacy of the releasing mechanism may be varied to suit conditions, by changes in the configuration of the contacting surface of the projection 38 and the lug 37.

The modifications depicted in Figs. 6 to 9 operate upon the same general principle, except that an abrasive instead of a percussive action is utilized to ignite the fuse 14. In this embodiment of the invention the fuse-clamping members are eliminated and lugs 44 are struck from the metal of the shell 11 and serve to hold the fuse in position. The fuse is provided with a plurality of 50 spaced fulminates 45, which project being the plane of the fuse. The hammer head is not provided with a firing pin, but that surface 46 of the head nearest the shell 11 is corrugated or abraded, and, when released, the corrugated surface 46 swings against and in contact with the fulminates 45 and ignites them.

The outer surface of the shell 11 makes close fit with the inner wall of the casing 55 1, on one side, serving to hold the timing

mechanism in position, the fuse 14 extending downwardly to the cap 15, on the other side, as illustrated.

From the foregoing it is obvious that I have interposed a delay in the firing of the 70 charge, after the timing mechanism has operated to activate the first of the train of instrumentalities leading to the explosion. The spring 32 is very powerful, and snaps the hammer head against the face of the 75 member 16 with considerable noise, giving audible indication that the fuse 14 has been ignited. Furthermore if the device is in the hands of the operator at the time, the operator may easily feel the jar when the 80 hammer strikes the member 16. The fuse is of the slow-burning variety, and any length desired may be interposed between the igniting device and the cap 15. Consequently, in case of accidental lighting of the 85 fuse, as set forth, ample time is provided to permit the operator to take off the cap 2, lift out the timing mechanism, and cut the fuse before the percussion cap 15 is exploded. 90

The clock 5 is of course equipped with the usual alarm bell which sounds as the shaft 8 rotates. Therefore, if the alarm setting is faulty and rotation of the shaft 8 springs the mechanism, the ringing of the alarm 95 bell warns the operator that the fuse has been ignited.

In my companion application, Ser. No. 57,452 of even date herewith I show a structure wherein the timing mechanism is enclosed in a transparent casing which enables the operator to view the mechanism and fuse. In this structure if the fuse is inadvertently ignited the operator breaks the 100 glass casing and pulls out and disrupts the 105 fuse.

Modifications of the structure herein set forth may be suggested to those skilled in the art, but my invention covers all embodiments falling fairly within the scope of the 110 appended claims.

What I claim is:

1. A bomb including a casing having an explosive charge confined therein, and a fulminated fuse leading to the charge, in combination with fuse-igniting means comprising a time piece provided with an alarm shaft, spring actuated mechanism adapted to contact and light the end of the fuse, and means carried by said alarm shaft and adapted to prevent operative actuation of 115 said spring mechanism, during one position of said alarm shaft.

2. A bomb including a casing having an explosive charge confined therein, and a fulminated fuse leading to the charge, in combination with fuse-igniting means comprising a time piece provided with an alarm shaft, spring actuated mechanism adapted to contact and light the end of the fuse, 120 125 130

means carried by said alarm shaft and adapted to prevent operative actuation of said spring mechanism, during one position of said alarm shaft, and additional means carried by said shaft for causing actuation of said spring-mechanism during rotation of the shaft.

3. A bomb including a casing having an explosive charge confined therein, and a fulminated fuse leading to the charge, in combination with fuse-igniting means comprising a time piece provided with an alarm shaft, a spring-actuated firing pin mounted adjacent the time piece and adapted for actuation to ignite the fuse, a detent adapted to lock the firing pin in armed position, and a cam carried by said alarm shaft adapted, under rotation of the latter, to move the detent and release the firing pin.

20 4. A bomb including a casing having an explosive charge confined therein, and a fulminated fuse leading to the charge, in combination with fuse-igniting means comprising a time piece provided with an alarm shaft, a spring-actuated firing pin mounted adjacent the time piece and adapted for actuation to ignite the fuse, a detent adapted to lock the firing pin in armed position, and a blade carried by said alarm shaft 25 and adapted to receive the end of said detent and prevent movement thereof during one position of said shaft.

5. A time-controlled igniter for bombs having a confined charge and a fulminated fuse leading thereto, comprising a time piece having an alarm shaft, a shell partially encircling said time piece, a clamp carried by said shell and adapted to receive the fulminated end of said fuse, an aperture leading through said clamp, a spring-actuated firing pin carried by said shell and pivotally mounted to swing into a path to project the pin into said aperture to explode the fulminate on said fuse, means for normally holding said pin in armed position, and means actuated by said time piece to release said pin at a predetermined time.

6. A time-controlled igniter for bombs having a confined charge and a fulminated fuse leading thereto, comprising a time piece having an alarm shaft, a shell partially encircling said time piece, a clamp carried by said shell and adapted to receive the fulminated end of said fuse, an aperture leading through said clamp, a spring-actuated firing pin carried by said shell and pivotally mounted to swing into a path to project the pin into said aperture to explode the fulminate on said fuse, a movable detent 50 adapted to retain said pin in armed position, and means carried by the alarm shaft and preventing releasing movement of said detent while said shaft is in one position.

60 7. A time-controlled igniter for bombs having a confined charge and a fulminated

70 fuse leading thereto, comprising a time piece having an alarm shaft, a shell partially encircling said time piece, a clamp carried by said shell and adapted to receive the fulminated end of said fuse, an aperture leading through said clamp, a spring-actuated firing pin carried by said shell and pivotally mounted to swing into a path to project the pin into said aperture to explode the fulminate on said fuse, a movable detent adapted to retain said pin in armed position, means carried by the alarm shaft and preventing releasing movement of said detent while said shaft is in one position, and means carried by said shaft adapted to move said detent to release the firing pin, during movement of the alarm shaft in clockwise direction.

75 8. A time controlled igniter for bombs having a confined charge and a fulminated fuse leading thereto, comprising a time piece having an alarm shaft, a shell partially encircling said time piece, means carried by said shell for supporting the upper end of said fuse, a spring-controlled arm supported by the shell and adapted for swinging movement to contact the fulminated portions of the fuse and to ignite the latter, a detent normally positioned in the plane of swinging movement of said arm, and provided with means for contacting said arm and retaining it in "set" position, and means carried by the alarm shaft adapted to move said detent to release said arm when the said shaft rotates in a clock-wise direction.

80 9. A time controlled igniter for bombs having a confined charge and a fulminated fuse leading thereto, comprising a time piece having an alarm shaft, a shell partially encircling said time piece, means carried by said shell for supporting the upper end of said fuse, a spring-controlled arm supported by the shell and adapted for swinging movement to contact the fulminated portions of the fuse and to ignite the latter, a detent normally positioned in the plane of swinging movement of said arm and retaining it in "set" position, means carried by the alarm shaft adapted to move said detent to release said arm when the said shaft rotates in a clock-wise direction, and additional means carried by said alarm shaft adapted to prevent movement of said detent when the shaft is not rotating.

85 10. A time controlled igniter for bombs having a confined charge and a fulminated fuse leading thereto, comprising a time piece having an alarm shaft, a shell partially encircling said time piece, means carried by said shell for supporting the upper end of said fuse, a spring-controlled arm supported by the shell and adapted for swinging movement to contact the fulminated portions of the fuse and to ignite the latter.

- ter, a detent normally positioned in the plane of swinging movement of said arm, and provided with means for contacting said arm and retaining it in "set" position, 5 a blade extending laterally of said alarm shaft, and a slot in said blade adapted to receive the rear end of said detent and prevent movement thereof to releasing position while said shaft is not rotating.
- 10 11. A time controlled igniter for bombs having a confined charge and a fulminated fuse leading thereto, comprising a time piece having an alarm shaft, a shell partially encircling said time piece, means carried 15 by said shell for supporting the upper end of said fuse, a spring-controlled arm supported by the shell and adapted for swing-
- ing movement to contact the fulminated portions of the fuse and to ignite the latter, a detent normally positioned in the 20 plane of swinging movement of said arm, and provided with means for contacting said arm and retaining it in "set" position, a blade extending laterally of said alarm shaft, and a slot in said blade adapted to 25 receive the rear end of said detent and prevent movement thereof to releasing position while said shaft is not rotating, and a cam on the lower portion of said blade and adapted to move said detent to releasing 30 position during rotation of said shaft in clock-wise direction.

In testimony whereof I affix my signature.
ALBERT M. KING,
